UNITED STATES PATENT OFFICE

147,138

DESIGN FOR AN ORPHREY OR SIMILAR ARTICLE

Charles M. Muench, New York, N. Y.

Application December 23, 1946, Serial No. 135,724

Term of patent 7 years

(Cl. D3—32)

To all whom it may concern:

Be it known that I, Charles M. Muench, a citizen of the United States of America, residing in New York city, county and State of New York, have invented a new, original, and ornamental Design for an Orphrey or Similar Article, of which the following is a specification, reference being had to the accompanying drawing, forming part thereof.

In the drawing:

The figure is a plan view of the orphrey embodying the design.

I claim:

The ornamental design for an orphrey or similar article, substantially as shown.

CHARLES M. MUENCH.
